[57] CLAIM

The ornamental design for a furniture shelf, substantially as shown and described.

DESCRIPTION

FIG. 1 is a top plan view of a furniture shelf showing my new design;

FIG. 2 is a front elevational view thereof;

FIG. 3 is a right side elevational view thereof; and

FIG. 4 is a rear elevational view thereof;
